ATTORNEYS,

UNITED STATES PATENT OFFICE.

HENRY KROEGER, OF NEW YORK, N. Y.

CAPODASTRO-BAR FOR PIANO-FRAMES.

SPECIFICATION forming part of Letters Patent No. 351,326, dated October 19, 1886.

Application filed April 15, 1886. Serial No. 198,935. (No model.)

To all whom it may concern:

Be it known that I, HENRY KROEGER, of the city, county, and State of New York, have invented certain new and useful Improvements 5 in Capodastro-Bars for Piano-Frames, of which the following is a specification.

The object of my invention is to provide a new and improved capodastro-bar, which is so constructed as to press firmly on the strings and prevent vibrations of those parts of the strings between the bridge and the tuning-pins, to which the strings are fastened.

The invention consists in a bar having its under side provided with a slightly-rounded ridge, against which the strings rest and exert an upward or outward pressure, said bar being provided at suitable intervals with feet which are rested against the frame of the piano, and are of such size as to hold the ridge 20 on the inner side of the bar at a certain distance from the face of the frame of the piano. Screws are passed through holes in the bar at the feet, and the strings rest against the ridge at the inner side of the bar between said feet.

25 In the accompanying drawings, Figure 1 represents an upright piano with my improved capodastro-bar, parts of the casing being broken out. Fig. 2 is an end view of the piano, parts being broken out and others in section. Fig. 3 is an enlarged view of the capodastro-bar and bridge. Fig. 4 is an enlarged cross-sectional view of the same on line *x x*, Fig. 3; and Fig. 5 is an enlarged cross-sectional view of the same on line *y y*, Fig. 3.

35 Similar letters of reference indicate corresponding parts.

The bar A, which is made of cast metal, is provided on its under or inner side with a slightly-curved ridge, B, against which the 40 strings C rest with an upward or outward pressure, said strings being fastened to the tuning-pins D, driven in the frame E, in the usual manner.

The bar A is located between the pins D 45 and the bridge-piece F, secured to the frame E, and having an outwardly or upwardly projecting flange, G, on the outer edge of which the strings C rest with a downward or inward pressure.

50 The bar A is provided on its under or inner side, at intervals, with the feet H, which are

arranged about at right angles to the longitudinal axis of the bar, and have a greater length than the width of the bar, for the purpose of distributing the bearing-surface of the 55 bar on the frame E over as large a surface as possible. The bearing-surfaces of the feet H are a short distance from the ridge B of the bar A, so that when the bearing-surfaces of the said feet rest on the front of the frame E the 60 ridge B, against which the strings rest, will be a short distance from the front of the frame. Screws J are passed through holes of the bar A at the feet H and screwed into the frame E.

The strings C pass under the capodastro-bar 65 in the spaces between the feet H, a number of strings being between each bearing-foot H. The bridge-piece F, which may have its flange in its inner or outer edge—that is to say, on the edge nearest to the bar A or farthest 70 from the same—is an independent piece, and is fastened on the frame E by screws. Both bearing-sections of the feet H rest on the front of the frame E, as shown in Fig. 4, or one of the bearing-surfaces may rest on the bridge-piece F at that edge opposite the one provided with the flange G, as shown in Fig. 5.

By providing the bar in the manner described, the strings are held firmly and taut, and the part between the flange G and the 80 tuning-pins D cannot vibrate, which is very desirable, as I have found that the quality of the tone is materially improved by holding the strings as rigidly and firmly as possible. As all the feet of the bar rest on the frame of the 85 piano, and as all the feet have the same height, all the strings throughout the registers at which the bars are provided will have the same bearing, and thus the quality of the tone will be even. The shape of the bar A and bridge-piece F conforms to the shape of the row of tuning-pins. As I provide the holes for the fastening-screws J at those parts of the bar A at which the feet are located, the said screws do not interfere with the strings, as the strings 95 are all passed under the bar between the feet, as stated above.

The said bar may be provided in grand, square, or upright pianos.

Having thus described my invention, I claim 100 as new and desire to secure by Letters Patent—

1. In a piano, the combination, with a frame,

of a capodastro-bar provided on its under side with a ridge against which the strings rest, and at suitable intervals with feet which rest directly on the surface of the frame, substantially as set forth.

2. The combination, with a piano, of a capodastro-bar provided on its under side with a ridge forming the bearing - surface for the strings, feet on the bar at suitable intervals, to said feet resting directly on the face of the

frame and provided with screw-holes, and screws passed through the holes in the feet and into the frame, substantially as set forth.

In testimony that I claim the foregoing as my invention I have signed my name in presence of two subscribing witnesses.

HENRY KROEGER.
